SUPPORT FOR FRAGILE ARTICLES

Ernest L. Shepard, Fairfield, Maine

Application September 13, 1950, Serial No. 12,169

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for Support for Fragile Articles, of which the following is a specification, reference being had to the accompanying drawing, forming part thereof.

Fig. 1 is a top plan view of a support for fragile articles, embodying my new design;

Fig. 2 is a front elevational view of the support shown in Fig. 1; and

Fig. 3 is a vertical sectional view taken on line 3—3 of Fig. 1.

I claim:

The ornamental design for a support for fragile articles, as shown.

ERNEST L. SHEPARD.
